UNITED STATES PATENT OFFICE.

FRED ARTHUR SKETCHLEY, OF EAST SAUGUS, MASSACHUSETTS.

TRAIN-CONTROL SYSTEM.

1,314,439.

Specification of Letters Patent. Patented Aug. 26, 1919.

Application filed August 30, 1918. Serial No. 252,082.

To all whom it may concern:

Be it known that I, FRED ARTHUR SKETCHLEY, a citizen of the United States, residing at East Saugus, in the county of 5 Essex and State of Massachusetts, have invented new and useful Improvements in Train-Control Systems, of which the following is a specification.

This invention relates to new and useful 10 improvements in train control systems, and the principal object of the invention is to provide means adapted to be operated by one train for moving a track obstruction into upright position so that this obstruction 15 will operate mechanism on another train for cutting off the steam supply of said train and applying the brakes. The invention includes among other features a series of casings located along the track, each casing 20 containing magnets, a plate movably mounted in the casing and adapted to be actuated by said magnets, a rod connected with the plate and adapted to be operated by the passing train and a series of circuits 25 controlled by said plate and leading to the other casings and to the means for actuating the track obstruction.

The invention also consists in certain 30 other features of construction and in the combination and arrangement of the several parts, to be hereinafter fully described, illustrated in the accompanying drawings and specifically pointed out in the appended claims.

35 In describing my invention in detail, reference will be had to the accompanying drawings wherein like characters denote like or corresponding parts through the several views, and in which:—

40 Figure 1 is a diagrammatic view of my invention,

Fig. 2 is a sectional view of one of the casings,

Fig. 3 is a detail view showing the arrangement of the train operated rod,

Fig. 4 is a view taken at right angles to Fig. 2,

Fig. 5 is a detail view of one of the spring supports for the plate,

50 Fig. 6 is a diagrammatic view of the invention applied to a crossing.

In these figures 1 indicates the pair of rails of the track while 2, 3, and 4 indicate the casings located along the same. Each 55 of these casings carries a partition plate 5 made of fiber or the like and the cover plate

6. As will be seen the casing is located below the track and the center thereof below one rail. This rail immediately above the casing is provided with a slot 7 to receive the end of a rod 8 which projects from the casing. The lower end of this rod is slidably mounted in the partition 5 with its upper end extending through the cover plate and said slot in the rail. The rod 60 carries a plate 9. The upper end of the rod is of segmental shape as indicated at 10 so that the part thereof projecting above the rail is of curved shape. The cover of the casing carries a pair of magnets 11 projecting downwardly therefrom into the casing and these magnets are located in an electric circuit 12 which is connected with a pair of contacts 13 in the adjacent casing. The contacts 13 in the first mentioned casing are 65 connected with the magnets of the casing in the rear thereof. These contacts are mounted on insulated blocks 14 secured to the walls of the casing and spring plates 15 are pivoted to the upper faces of said blocks 70 by means of the pins 16. In this way the plates 15 may be swung upwardly but said plates are held against downward movement by blocks 17 secured to the blocks 14.

A, B, and C, indicate small casings placed 75 along the track and each casing has mounted therein a pivoted member 18. This member passes through a slot in the top of the casing and when in raised position will be struck by a part on the train and this part 80 will operate mechanism to shut off the steam supply to the engine and apply the brakes and thus stop the train. The member 18 is pivoted at its lower end and an arm 19 is connected with this lower end in such a manner that the weight of the arm will cause the member to normally rest in its lowest position. A magnet 20 is carried by the cover of the casing and an armature 21 is carried by the arm 19 so that when the magnet 20 is energized it will attract the armature and raise the arm and so move the member 18 into operative position. This magnet 20 is electrically connected with a pair of contacts 22 in the adjacent casing.

When a train passes over casing 2, the wheels thereof will depress the rod 8 and thus move the plate 9 into engagement with the contacts 13. This will complete the circuit to the magnets of the casing in the rear. 110 This action will force the plate 9 by the spring plates 15, said plates bending to al-

low the plate 9 to pass by. When the train passes over casing 3 and pushes rod 8 down forcing plate 9 into engagement with the contacts 13 in said casing the circuits to magnets 11 in casing 2 will be closed so that the plate 9 will be raised into engagement with the contacts 22 so as to close the circuit to magnet 20 in casing A, whereby the member 18 in said casing will be raised into operative position. If a train should be following the train on casing 3 it would come in contact with said member 18 in casing "A" and thus be stopped, as said member 18 will actuate a part on the engine which will operate mechanism to shut off the steam applied to the engine and apply the brakes as before described. It will be seen that as the plate 9 moves upwardly it will swing the spring plates 15 on their pivots so that these plates will not interfere with the upward movement of the plate 9. As the plate 9 leaves the contacts 13 the circuit to the magnets in casing 2 will be broken so that plate 9 in said casing 2 will drop back on to the spring plates 15 and will be supported by said plates. This will deenergize the magnet of the casing in rear of "A" so as to permit the operating member in said casing to assume its inoperative position.

When the train passes over casing 4 it will force plate 9 into engagement with the contacts 13 so as to close the circuit to the magnets in casing 3 thus causing them to raise plate 9 in said casing 3 which will close the circuit to magnet 20 in casing "B," raising member 18 into operative position. The upward movement of plate 9 in casing 3 will break the circuit to the magnets in casing 2 so that the plate 9 in said casing 2 will drop back on the supporting springs 15 and thus break the circuit to the magnet in casing "A," thus permitting the operating member in said casing "A" to assume its inoperative position.

Fig. 6 shows the invention applied to a crossing. In this view two of the devices, indicated by the reference letters D and F are placed on one track while the devices E and G are placed on the other track. These devices are so arranged that when a train passes over the device D the track projections will be raised at the devices E and G so

as to stop a train from passing over the crossing on this track. It will be understood that the projection of the device in rear of the device D will also be raised. When the train reaches device F it will energize the magnets in device D and this will break the circuits E and G, so as to permit a train to pass on the track on which devices E and G are located.

It is thought from the foregoing description that the advantages and novel features of my invention will be readily apparent.

I desire it to be understood that I may make such changes in the construction and in the combination and arrangement of the several parts, provided that such changes fall within the scope of the appended claims.

Having described my invention what I claim and desire to secure by Letters-Patent is:

1. A train control system comprising a series of casings, a track obstruction located adjacent each casing, electric means controlling said obstructions, magnets in each casing, a switch plate in said casing controlling said electrical means and operated by the magnets, an electric circuit connecting the magnets in each casing to contacts in the adjoining casing and a rod adapted to be operated by the train and connected with the switch plate for forcing said plate into engagement with said contacts.

2. A train control system comprising a series of track obstructions, magnetic means for controlling said obstructions, a series of casings, contacts in each casing, a circuit connecting some of said contacts with the magnetic means, magnets in each casing, a circuit connecting said magnets in one casing with the other contacts in the adjacent casing, a switch plate in each casing adapted to close the circuit to the magnetic means when the magnets in said casing are energized, a train operated rod connected with said switch plate for moving the same into engagement with the other contacts and closing the circuits to the magnets and hinged spring plates for supporting said switch plate in inoperative position.

In testimony whereof I affix my signature.

FRED ARTHUR SKETCHLEY.
